HEMMING ATTACHMENT FOR SEWING MACHINES

John P. Enos, Elizabeth, N. J., assignor to The Singer Manufacturing Company, Elizabeth, N. J., a corporation of New Jersey

Application March 6, 1940, Serial No. 322,434

15 Claims. (Cl. 112—141)

This invention relates to hemming attachments for sewing machines and particularly to a narrow hemming attachment for edge-folding the margin of a cravat or handkerchief and directing the same so folded to the stitching mechanism of a sewing machine.

A primary object of the invention is to provide a hemming attachment of the spiral type having provision whereby its capacity can be varied automatically in response to the passage therethrough of unequal thicknesses of material.

Another object of the present invention is the provision of a yieldable spiral section which functions to maintain the material being hemmed in engagement with the spiral folding-edge of the attachment, whereby the tendency of the material to shift laterally out of the attachment during the hemming operation is reduced to a minimum.

A further object of the invention is to provide a hemming attachment whereof one of the spiral scrolls, which frequently breaks during usage because of frailty resulting from its required special heat-treatment, can be replaced conveniently and quickly, thereby increasing materially the life of the attachment.

A still further object of the invention is the provision of a hemming attachment having the above noted features, the elements of which are simple in construction, inexpensive to manufacture, and susceptible of convenient assembly and replacement.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings:

Fig. 1 is a side elevation of a scroll-hemmer embodying the present invention.

Fig. 2 is a top plan view of the scroll-hemmer, partly in section, showing the pivotal mounting for the yieldable scroll-section.

Fig. 3 is a vertical section taken substantially along the line 3—3, Fig. 1.

Fig. 4 is a vertical section taken along the line 4—4, Fig. 1.

Fig. 5 is a vertical section taken along the line 5—5, Fig. 1.

Fig. 6 is a perspective view of the casing inverted to show its construction.

Fig. 7 is a perspective view of the bearing-member which pivotally supports the yieldable scroll-section.

Fig. 8 is a side elevation, partly in section, of a modification of the scroll-hemmer illustrated in Fig. 1.

Fig. 9 is a top plan view, partly in section, showing a different form of yieldable mounting for the movable scroll-section.

Fig. 10 is a top plan view with the movable scroll-section positioned in its extreme opened position.

Fig. 11 is a vertical sectional view taken substantially along the line 11—11, Fig. 8.

Fig. 12 is a side elevation, partly in section, of a second modification, showing a scroll-hemmer whereof the secondary scroll-section is adapted to be initially adjusted and maintained in such position by a set-screw.

Referring more in detail to the drawings, the hemming attachment illustrated in Figs. 1 to 7, inclusive, comprises a base-plate 1 fitted at one end with a depending securing-screw 2 adapted to project through a suitable aperture 3 provided in the usual cloth-plate 4 of a conventional sewing machine and have threaded thereon a clamp-nut 5. Integral with the other end of the base-plate 1 is a depending end-portion 6 entering a recess 7 in the cloth-plate 4 to more securely retain the hemmer in proper alignment relative to the stitching mechanism. On the upper surface of the base-plate 1 is soldered, or otherwise fastened thereto, a substantially C-shaped bracket 8, the upper horizontal limb of which 35 supports a primary spirally formed scroll-section 9. The primary scroll-section is made of relatively heavy stock and is not adapted to yield appreciably in response to inequalities in the thickness of materials being hemmed.

Cooperating with the primary scroll-section 9 is a relatively thin secondary scroll-section 10 twisted with the primary scroll-section to provide between them a spiral passageway 11 extending toward the needle and within which the marginal edge of the fabric is adapted to be placed. The secondary scroll-section 10 is preferably composed of spring steel and is heat treated to render it inherently yieldable to a limited extent. In scroll-hemmers of the type in question as previously constructed, an example of which is shown in the U. S. patent to C. H. Willcox, No. 43,657, dated July 26, 1864, the secondary scroll-section was formed with an integral shank permanently secured upon the base-plate. In this construction, the capacity of the hemmer

was limited by the degree of inherent flexibility of the secondary scroll-section. If the capacity of the hemmer was exceeded, excessive resistance to the passage of fabric through the hemmer was experienced, which resulted either in an imperfectly formed hem or a choked hemmer. In addition, since the secondary scroll-section was rigidly secured to the base-plate the capacity of the spiral fabric-receiving passageway 11 adjacent the mouth of the hemmer was definitely established, and if a material of less thickness than the depth of the spiral passageway was used, it was essential that the fabric be presented to the hemmer in such a way as to completely fill widthwise the fabric-receiving passageway 11 at the mouth of the hemmer. This was necessary because the spiral fabric-turning edge 12 of the secondary scroll-section 10, being spaced a predetermined distance from the primary scroll-section 9, did not pinch the fabric against the primary scroll-section and cause it to definitely follow the spiral fabric-turning edge 12.

The present invention resides in the provision of an adjustable or yieldable secondary scroll-section whereby the fabric-turning edge thereof is maintained yieldingly in contact with the primary scroll-section to effectively control the fabric-margin being folded, and whereby the capacity of the hemmer may be varied in response to the thickness of the material being hemmed. To this end the secondary scroll-section 10 is attached at one end to a cylindrical shank 13 journaled for limited oscillation in the open-ended bearing apertures 14 formed in the up-turned end-portions 15 and 16 of a bearing-member 17. The bearing-member 17 is preferably fastened upon the base-plate 1 by a screw 18. Formed on the upturned end-portion 16 of the bearing-member 17 are two horizontal lugs 19 which, as shown in Fig. 1, are adapted to be received in the horizontal limbs of the bayonet-slots 20 provided in the side-walls of a hollow semi-cylindrical casing 21. The casing 21 is tapered at its forward end, as at 22, to facilitate the passage thereover of the fabric being hemmed. Extending forwardly from the base of the tapered end 22 of the casing 21 is a finger 23 which projects beneath a suitable bracket 24 riveted or otherwise secured to the base-plate 1. The finger 23 and the screw 18 detachably secure the casing and the parts housed and supported thereby upon the base-plate 1.

As observed in Figs. 1 and 2, the cylindrical arbor 13 adjacent the upturned end-portion 16 of the bearing-member 17 is offset, as at 25, to prevent endwise movement of the arbor in the direction of the normal feed of the fabric through the attachment, and extended, as at 26, to provide a support for a coil-spring 27. The coil-spring has one of its ends secured to the extended portion 26 of the arbor and its other end 28 bearing against the casing 21. The function of the coil-spring 27 is to yieldingly bias the secondary scroll-section in a clockwise direction (when the hemmer is viewed in the direction of travel of the fabric) about the longitudinal axis of the arbor 13 to cause the spiral fabric-turning edge 12 of the secondary scroll-section to pinch the fabric against the primary scroll-section and thereby forcibly cause it to follow the fabric-turning edge 12. In addition, the pinching of the fabric between the primary and secondary scroll-sections prevents the fabric from working itself out of the hemmer during its passage therethrough.

In the event the secondary scroll-section is broken or otherwise damaged, it can be conveniently replaced by first removing the screw 18, then sliding the casing 21 and the elements carried thereby rearwardly to release the finger 23 from the bracket 24. The casing 21 may then be inverted to expose the bearing-member 17 which can be shifted relative to the casing to release the lugs 19 from the bayonet-slots 20. When the bearing-member 17 is released from the casing 21 the arbor 13 carrying the secondary scroll-section 10 drops out of the open-ended bearing-apertures 14, permitting the coil-spring 27 to be conveniently removed from the arbor. The damaged scroll-section can then be discarded and a new one substituted therefor. The hemmer may be assembled by following the above described steps in reverse order.

The hemmer shown in Figs. 8 to 11, inclusive, is a modification of the device illustrated in Figs. 1 to 7, inclusive. In the modification, the secondary scroll-section 10 is formed with a substantially U-shaped shank 29, the horizontal portion of which is adjustably or slidably held in contact with the upper surface of the base-plate 1 by an overlying retaining strip 30 secured at one end to the base-plate. As shown in Fig. 11, the retaining-strip 30 is spaced from the upper surface of the base-plate to permit the shank 29 of the secondary scroll-section to shift laterally in response to inequalities in the thickness of the fabric being hemmed. The retaining-strip 30 is bent at 31 to provide a stop against which the side of the shank 29 of the secondary scroll-section is yieldingly maintained by a spring 32 coiled about an upstanding lug 33 preferably formed as a continuation of the securing-screw 2. The spring 32 is formed with two arms 34 and 35, the arm 34 being bent at its free end and hooked through an aperture 36 provided in the vertical limb 37 of the shank of the secondary scroll-section. The arm 35 is also bent at its free end and is disposed beneath a tongue 38 struck-up from the base-plate 1. Housing the spring 32 and the U-shaped shank 29 of the secondary scroll-section 10 is the casing 21 which is secured in place by a screw 39 threaded into the lug 33.

In the modification illustrated in Figs. 8 to 11, inclusive, the secondary scroll-section is adapted to yield transversely of the line of feed in response to inequalities, such as cross-seams, in the thickness of the fabric being hemmed. In Fig. 9 the shank 29 of the secondary scroll-section is in contact with the stop 31, while in Fig. 10 the shank 29 is shown shifted away from the stop 31 crosswise of the seam-line. This adjusting or shifting of the secondary scroll-section permits an automatic change in the capacity of the scroll-hemmer, thereby adapting the device to accommodate a variety of different materials and also to eliminate possible overloading of the hemmer resulting from traversing cross-seams and the like in the fabric. It will be understood that the secondary scroll-section can be readily replaced by removing the casing 21 and unhooking the arm 34 of the spring 32 from the shank of the secondary scroll-section.

Referring now to Fig. 12, the hemmer disclosed is a second modification. It will be observed that in this device the secondary scroll-section 10 is soldered, or otherwise secured, to a cylindrical shank 40 adapted to be adjustably received in an aperture 41 provided in the casing 21. Threaded into the bottom of the casing 21 is

an adjusting set-screw 42 which bears against the shank 40 and locks the secondary scroll-section in the desired position. The head of the screw 42 projects through a clearance aperture 43 in the base-plate 1. The casing 21 is fastened to the base-plate by two screws 44 and 45. In this modification the capacity of the scroll-hemmer is not automatically varied to accommodate inequalities in the thickness of the fabric, but may be initially set to the desired amount by removing the hemmer from the cloth-plate of the sewing machine to expose the adjusting set-screw 42, which can be unscrewed to release the shank 40 of the secondary scroll-section. The secondary scroll-section can then be turned about the axis of the shank 40 to the desired position and then locked in such position by the set-screw 42. It will be seen that in the case of injury to the secondary scroll-section it can be readily replaced by releasing the set-screw 42 and substituting a new scroll-section for the damaged scroll-section.

In each of the modifications illustrated, it will be seen that the base-plate 1 in advance of the receiving end of the hemmer has mounted thereon the casing 21. The casing in its preferred form is semi-cylindrical and functions to encompass the shank of the secondary scroll-section 10 of each of the modifications, and also to provide a smooth fabric-supporting platform for facilitating the proper presentation of the fabric to the fabric-receiving passageway 11 defined by the spiraled scroll-sections.

Having thus set forth the nature of the invention, what I claim herein is:

1. A hemming attachment for sewing machines comprising in combination, a base-plate, a longitudinally spiraled primary scroll-section secured to said base-plate, a longitudinally spiraled secondary scroll-section cooperating with said primary scroll-section to define between them a fabric-receiving passageway, a shank to which said secondary scroll-section is fixed, and means for supporting said shank for circular adjustment about the longitudinal axis of said shank.

2. A hemming attachment for sewing machines comprising in combination, a base-plate, a longitudinally spiraled primary scroll-section secured to said base-plate, a longitudinally spiraled secondary scroll-section twisted with said primary scroll-section to define a fabric-receiving passageway, a shank to which said secondary scroll-section is secured, and means including a spring for supporting said shank for yieldable turning movement about the longitudinal axis of said shank to vary the capacity of the fabric-receiving passageway.

3. A hemming attachment for sewing machines comprising in combination, a base-plate, a longitudinally spiraled primary scroll-section secured to said base-plate, a longitudinally spiraled secondary scroll-section having a fabric-turning edge and twisted with said primary scroll-section to define a fabric-receiving passageway, a shank to which said secondary scroll-section is secured, a bearing member provided with a bearing aperture in which said shank is journaled, and a spring adapted to bias the fabric-turning edge of said secondary scroll-section toward said primary scroll-section to forcibly cause the fabric to follow said fabric-turning edge.

4. A hemming attachment for sewing ma-

chines comprising in combination, a base-plate, a longitudinally spiraled primary scroll-section secured to said base-plate, a longitudinally spiraled secondary scroll-section having a fabric-turning edge and twisted with said primary scroll-section to define a fabric-receiving passageway, a shank to which said secondary scroll-section is secured, a bearing member secured to said base-plate and formed with an open-ended bearing aperture in which said shank is journaled, a spring adapted to bias the fabric-turning edge of said secondary scroll-section toward said primary scroll-section to forcibly cause the fabric to follow said fabric-turning edge, and a casing adapted to house said spring and close the open end of said bearing aperture to prevent the dislodgment of the shank of said secondary scroll-section.

5. A hemming attachment for sewing machines comprising in combination, a base-plate, a longitudinally spiraled primary scroll-section secured to said base-plate, a longitudinally spiraled secondary scroll-section having a fabric-turning edge and twisted with said primary scroll-section to define a fabric-receiving passageway, a shank to which said secondary scroll-section is secured, a bearing member formed with a plurality of lugs and with a bearing aperture in which said shank is journaled, a spring adapted to bias the fabric-turning edge of said secondary scroll-section toward said primary scroll-section to forcibly cause the fabric to follow said fabric-turning edge, and a casing adapted to house said spring and said bearing member, said casing being provided with a plurality of bayonet-slots adapted to receive the lugs of said bearing member thereby to secure the casing in position upon the base-plate.

6. A hemming attachment for sewing machines comprising, a base-plate having a bracket, a longitudinally spiraled primary scroll-section secured to said base-plate, a longitudinally spiraled secondary scroll-section having a fabric-turning edge and twisted with said primary scroll-section to define a fabric-receiving passageway, a shank to which said secondary scroll-section is secured, a bearing member attached to said base-plate and apertured to receive the shank of said secondary scroll-section, a spring adapted to bias the fabric-turning edge of said secondary scroll-section toward said primary scroll-section to forcibly cause the fabric to follow said fabric-turning edge, a casing adapted to house said spring and facilitate the passage of the fabric thereover, said casing being formed with a finger adapted to project beneath the bracket on said base-plate, and means for detachably securing the casing to said bearing-member.

7. A hemming attachment for sewing machines comprising, a base-plate, a longitudinally spiraled primary scroll-section secured to said base-plate, a longitudinally spiraled secondary scroll-section twisted with said primary scroll-section to define a fabric-receiving passageway, a shank fastened to said secondary scroll-section and connected to said base-plate for lateral slideable movement relative to said primary scroll-section, and a spring for biasing said secondary scroll-section toward said primary scroll-section.

8. A hemming attachment for sewing machines comprising, a base-plate, a longitudinally spiraled primary scroll-section secured to said base-plate, a longitudinally spiraled secondary

scroll-section twisted with said primary scroll-section to define a fabric-receiving passageway, a shank integral with said secondary scroll-section and having a horizontal portion in contact with said base-plate, a retaining strip secured to said base-plate and overlying said horizontal portion for slidably maintaining said shank on said base-plate, and a spring engaging said shank for biasing said secondary scroll-section toward said primary scroll-section.

9. A hemming attachment for sewing machines comprising, a base-plate, a longitudinally spiraled primary scroll-section secured to said base-plate, a longitudinally spiraled secondary scroll-section twisted with said primary scroll-section to define a fabric-receiving passageway, a shank integral with said secondary scroll-section and connected to said base-plate for limited transverse movement, a spring adapted to bias said secondary scroll-section toward said primary scroll-section, and a detachable hollow casing adapted to house said shank and spring to facilitate the passage of fabric thereover.

10. A hemming attachment for sewing machines comprising, a base-plate having an up-standing lug, a spiraled primary scroll-section secured to said base-plate, a spiraled secondary scroll-section twisted with said primary scroll-section to define a fabric-receiving passageway, a shank integral with said secondary scroll-section and having a horizontal portion in contact with said base-plate, means for slidably maintaining said shank upon said base-plate, a spring coiled about said upstanding lug and having one of its limbs engaging the shank of said secondary scroll-section for biasing the latter toward said primary scroll-section, and a hollow casing secured in position to house said shank and spring by a fastening screw threaded into said upstanding lug.

11. A hemming attachment for sewing machines comprising, a base-plate, a longitudinally spiraled primary scroll-section secured to said base-plate, a longitudinally spiraled secondary scroll-section twisted with said primary scroll-section to provide a fabric-receiving passageway, means for supporting said secondary scroll-section for adjustment about an axis parallel to the line of the normal feed of the fabric through the hemmer, and means for locking said secondary scroll-section in adjusted position.

12. A hemming attachment for sewing machines comprising, a base-plate, a longitudinally

spiraled primary scroll-section secured to said base-plate, a longitudinally spiraled secondary scroll-section twisted with said primary scroll-section to provide a fabric-receiving passageway, a shank integral with and arranged longitudinally of said secondary scroll-section, a casing mounted upon said base-plate and apertured to adjustably receive said shank, and a set-screw engaging said shank for locking the secondary scroll-section in adjusted position.

13. A hemming attachment for sewing machines comprising, a base-plate, a longitudinally spiraled primary scroll-section secured to said base-plate, a longitudinally spiraled secondary scroll-section twisted with said primary scroll-section to provide a fabric-receiving passageway, a cylindrical horizontal shank integral with and arranged longitudinally of said secondary scroll-section, a casing detachably mounted upon said base-plate and apertured to adjustably receive said shank, and a set-screw threaded into said casing and engaging said shank for locking the secondary scroll-section in adjusted position, said set-screw being accessible through said base-plate.

14. A hemming attachment for sewing machines comprising, a base-plate, a pair of adjacent longitudinally spiraled scroll-sections defining between them a fabric-receiving passageway having a receiving end and a delivery end, a shank formed on one of said scroll-sections adjacent the receiving end of said fabric-receiving passageway, and a casing secured upon said base-plate in advance of the scroll-sections and encompassing said shank, said casing providing a fabric-supporting platform for facilitating the proper presentation of the fabric to the spiraled scroll-sections.

15. A hemming attachment for sewing machines comprising, in combination, a base-plate, a first longitudinally spiraled scroll-section supported by said base-plate, a second longitudinally spiraled scroll-section positioned to define with said first scroll-section a fabric-receiving passageway, a support for said second scroll-section, and means for adjustably supporting said second scroll-section on said support for bodily movement of said second scroll-section relative to said first scroll-section to augment the inherent flexing of the scroll-sections to vary the capacity of the fabric-receiving passageway.

JOHN P. ENOS.
